UNITED STATES PATENT OFFICE.

JOHN HILL, OF WORCESTER, MASSACHUSETTS.

STOCK-RELEASING DEVICE.

1,307,355.

Specification of Letters Patent. Patented June 24, 1919.

Application filed August 31, 1918. Serial No. 252,134.

To all whom it may concern:

Be it known that I, JOHN HILL, a citizen of Finland, residing at Worcester, in the county of Worcester and State of Massachusetts, have invented a new and useful Stock-Releasing Device, of which the following is a specification.

This invention relates to a device for releasing stock from a barn or the like, and the principal objects thereof are to improve this type of apparatus in such a manner as to avoid the difficulties which have prevented devices for this purpose being put into practical use heretofore; to provide means whereby the stock will be released from their stalls in case of fire; to provide a weight for operating the releasing devices at the stalls and door which, instead of hanging so as to exert a pull thereon 15 all the time or a pull on the destructible cord which frees it, will be held mechanically in its raised position under all ordinary conditions and will not put any strain on any of its connections until it is released by fire. In this way the flexible connections are relieved of all abnormal strain throughout the period when they are in a state of rest and their durability greatly increased. The invention also involves means 20 by which the device can be set off by hand either for testing purposes or in cases of emergency, and details of construction as will appear hereinafter.

Reference is to be had to the accompanying drawings in which—

Figure 1 is an elevation of one wall of a barn showing a preferred embodiment of this invention applied thereto;

Fig. 2 is a plan of the connections under 40 the roof for setting off the device in case of fire;

Fig. 3 is a side elevation of the operating weight and its supporting mechanism on enlarged scale;

Fig. 4 is a similar view of the front thereof looking in the direction of the arrow 4 in Fig. 3 and showing in dotted lines the position of the parts when the latch is released to drop the operating weight;

Fig. 5 is a front view of a releasing device for the stock;

Fig. 6 is a side view of the same;

Fig. 7 is a plan of one element thereof;

Fig. 8 is a rear elevation of the door of

the stable showing its connection with this apparatus;

Fig. 9 is a view of a modified form of individual stock releasing device;

Fig. 10 is a view of the destructible connection, and

Fig. 11 is a view of a modification.

The invention is shown as applied to a stock barn or stable, and as provided with an operating weight 10 which is normally held up in elevated position and which when released so as to drop on a stand 11 will release the stock and open a door or doors.

For the purpose of holding up this weight, it is shown as located in a casing 12 in an elevated position in the stable and provided with a pivoted bottom 13 on which the weight rests when the parts are not in operation. This pivoted bottom may be in the form of a bar extending across the bottom of the casing which is sufficient to hold up the weight. The casing is provided with a lug 14 on which is pivoted a latch 15. This latch is provided with a horizontal surface 16 adapted to support the free end of the bar 13 between two projections 17 extending from the lug 14. These projections are provided for accurately holding the bar against side motion. The horizontal surface 16 is located directly below the pivot 18 on which the latch 15 swings. Consequently when the bar 13 is raised between the projections 17 and the latch 15 swings over into the position shown in Fig. 3 in full lines, the latch will be held in that position by gravity.

The latch is shown as provided with two projections 19 and 20 extending in different directions from it. A pull upwardly on the end of the projection 19 or to the right on the end of the projection 20 will swing the latch, release the rod 13, and drop the weight 10. The projection 19 normally holds the latch in, and returns it to, operative position by gravity.

I will now describe the connections by 100 which the latch 15 can be released referring first to the projection 19. This is provided with a flexible connection 21 which can be made of any material not destructible by heat or fire, but I prefer to make it of 105 twisted wire which in itself is strong enough to resist the action of any ordinary fire. This flexible connection 21 passes over pul-

leys located in various places and is divided into two destructible strands 22 and 23. The strands, when they pass over the pulleys preferably are connected by metal but-
5 tons 28. These two strands are substan-
tially alike as shown, although they may
go to very different parts of the building,
but I have shown them both as divided and
extending up under the roof and passing
10 back and forth over pulleys so that they
are located at short distances apart and in
case of fire that affects the roof, some one
of them will necessarily be destroyed at
some point.

15 It is to be noted that each of these strands 22 and 23 is further divided and each half 29 passes over one of the two pulleys 24 and the other half 29 passes over the other of this pair of pulleys, and that these two
20 halves extend in opposite directions from these pulleys. Up to these pulleys 24 they are indestructible, but beyond them the twisted wire of which the strands 29 are formed is in short lengths connected to-
25 gether, by screw buttons 26 to facilitate in-
stallation and replacement. Each length
between buttons is made up of two or more
pieces of wire as shown in Fig. 10, soldered
together at intervals by solder 27, melting
30 at a temperature above 100 degrees F and
below any temperature likely to be attained
in any stable which catches fire.

On the end of each of these strands 29 is
35 a weight 25. These weights 25 are all alike,
and consequently under normal conditions
the two weights on the ends of each of the
halves 29 of the wire 22 will hold this in
what I call balanced condition, but if one of
these halves is broken its weight will drop
40 and the other weight 25 will then pull the
cord 22 along its course and thus pull up on
the arm 19. The same of course, is true of
the flexible connection 23. It will be seen
from this that it is the strand that remains
45 intact that operates the lever and not the
one that is broken or destroyed. This prin-
ciple I have employed throughout, because
it makes a positive acting device and does
not necessitate the holding of the weight 10
50 by means of these destructible connections
29 or the like.

On the lower arm 20 a similar device is
provided as two flexible indestructible con-
55 nections 31 and 32 are shown passing over
two pulleys 33 located adjacent to each other
and extending in opposite directions from
these pulleys. The strand 31 is further di-
vided where it passes under two pulleys 34
and its opposite destructible strands as 35
60 pass around the barn in any desired path
over pulleys so as to provide parts located
near enough together so that any fire along
the walls will destroy or break one of them.
Although I have shown these on only one
65 wall, it is to be understood that preferably

they extend all around the barn. On the end
each of these strands 35 is provided with a
weight 36, and, as in the roof construction,
when one of these strands breaks, its weight
36 drops and has no further effect, but the
70 other weight 36 is then free to descend, no
longer being counterbalanced by the oppo-
site weight, and it will pull the strand along
and pull on the arm 20 and then release the
latch. The other flexible connection 32 is
75 also divided and passes over two pulleys 38.
Its destructible ends are provided with
weights 39 or the like which are provided
with cords having rings 49 arranged in
80 some convenient position so that an attend-
ant can pull upon them in case of emergency,
or for the purpose of testing the device in
order to pull the latch 15 over and release
the weight 10.

It is to be noted that one of the strands 85
35 is shown as passing through uprights 40
and protected by plates or boards 41 in front
so that it will not be pulled or injured acci-
dentially. Although this is not shown
throughout the construction, it is preferred
90 to employ it. In this way it will be seen that
a positive acting arrangement is secured not
likely to be injured by accident except by
fire that will release the operating weight 10
and allow it to drop from its customary
95 place.

Having described the method of releasing
the operating weight 10, I will now describe
the effects that it produces, incidentally de-
scribing the mechanism illustrated.

The operating weight 10 is shown as pro-
vided with a grooved roll 50 at the top.
This engages a flexible connection in the
form of a cord, rope, wire, or chain 51 which
is preferably formed of a material not af-
fected by fire. It will be noted that this
connection 51 is not attached to the weight,
but simply rests on grooved guides or roll-
ers 52 on either side of the weight, and that
the fall of the weight makes a loop in it and
110 pulls the connection along toward the weight
from each side.

On this connection 51 are mounted fasten-
ing devices 53 which are located normally at
a distance from brackets 54 which support
the grooved rollers over which the connec-
tions pass. These brackets constitute stops
for the holders 53 to limit their motion.
When the connection 51 moves toward the
weight, the part of it at the left will move
120 to the right and will raise a plurality of
strands 55 connected with it. Each of these
in the form shown in Fig. 1 is connected
with a conical pin 56 arranged in vertical
position and located at the end of a strand.
125 This pin is connected with a cylinder 57
mounted in a tube 58 which protects the
cable 55 and guides the cylinder 57. When
in its normal position it passes down through
a hole 59 in a plate 60 which is located be-
130

tween two horizontal plates 61 secured to the wall of the stall in any desired way and preferably formed in one casting with a plate 62. They have holes for the passage 5 of the pin 56, as indicated in Figs. 5, 6 and 7. The plate 60 also is provided with means for securing cattle or other stock. When the above indicated action happens, the pin 56 is pulled out and the plate 60 releases so that 10 the animal is free to pull away and get out of the stall.

In Fig. 11 I have shown a modification in which the strand 55^a has a wedge 90 at the bottom normally entering a slot in a stationary rail 91 of a stanchion 92. When it is lifted, it allows the left-half of the stanchion to be opened by the animal. The right-half works in the ordinary way.

Another way in which the movement of 20 this connection 51, as above described, can release stock is to open a door. For that purpose I have shown a double door consisting of two parts 65 and 66. The part 65 is adapted to have a lock and to be locked 25 in any ordinary way, and these two parts ordinarily act together as a single sliding door. The part 65 is provided with two plates 67, each having a notch at 68. These plates are fixed to the door 65 removably. 30 On the door 66 is a bent lever 69 pivoted at 70 and on its end is a rod 71 which is pivotally connected with two latches 72 pivoted at 73. Each of these latches has a tooth for fitting in the notch 68 as indicated in full 35 lines in Fig. 8. A spring 74 is preferably provided for holding the parts in the locked position indicated. The strand 51 has a wedge-shaped or conical pin 63 normally hanging down and wedging itself between two rolls 64. Over one of these 40 passes a wire cable 75 having a weight 76 on one end and connected with the lever 69 at the other.

As stated, in ordinary practice this double 45 door is moved back and forth without any attention being paid to the latch construction, but when the strand 51 is raised, it releases the weight 76 and the lever 69 is pulled, thus raising the rod 71 and swinging 50 the two latches 72 upwardly on their pivots, thus releasing the door 66 from the locked door 65. The continued descent of the weight 76 pulls on the lever 69 and draws 55 the door 66 back so as to open it and leave a space between the two doors. Thus this constitutes another stock releasing device. After the weight 10 is restored to its normal position, the only thing required to connect the doors is to push them together as 60 the weight 76 does not pull on the lever 69, but the spring 74 tends to hold the parts in locking position.

The other end of the connection 51 is also 65 designed to perform useful functions. It is connected with the connection 77 which has

a metal member 78 upon it and a weight 79 at the bottom. This is connected with the connection 51 in such a way that when the weight 10 moves down it will allow the metal connector 78 to move down and electrically connect two metal plates 80 which completes a circuit and rings a bell 81 which may be located in the barn or in the house at a distance, or at a fire station. Any other electrical alarm device can be substituted for 75 the bell. A weight 82 is shown for normally holding the connection 51 taut. After being released so as to drop the weight is lifted back to normal position in any desired way and the latch caught under the 80 rod 13.

In the form shown in Fig. 9 I have provided a horizontal stock releasing device instead of a plurality of vertical ones. In this case the connection 55 pulls a rod 85 to 85 the left. This rod is provided with a series or horizontal pins 86 which, on being pulled to the left, release plates 87 in all respects similar to the plates 60 except that they are arranged vertically instead of horizontally. 90 In this case the weight 88 is used for the same purpose as the weight 82.

It will be understood, of course, that the device can be employed to release stock in other ways, to open other doors, to turn on 95 water from a sprinkling system, or for any other purpose desirable in the case of fire, and that the ones I have illustrated are shown mainly for the purpose of indicating the utilities to which the apparatus can be 100 put. But it will be seen that the device, whether used exactly in the way indicated or not, is of a durable and practical nature having no parts likely to get out of order, and that I have avoided the common error 105 of hanging the operating weight in such a way as to constantly pull on the devices to be operated, or on the destructible cord or the like.

Although I have illustrated and described 110 only two forms of the invention, I am aware of the fact that other modifications can be made therein by any person skilled in the art without departing from the scope of the invention as expressed in the claims. This 115 invention is not restricted to the specific form of door or destructible flexible connection illustrated herein. Therefore I do not wish to be limited to all the details of construction herein shown and described, but 120 what I do claim is—

1. In a device of the character described, the combination with an operating weight, means constructed and adapted to be operated in case of fire for releasing the weight 125 so as to allow it to descend, an operating flexible connection passing by the weight movably connected thereto, and running in opposite directions therefrom, whereby the descent of the weight will pull both ends 130

of said connection lengthwise toward the weight or if one end should fail to work will operate the other, and means operated by said connection for releasing stock.

- 5 2. In a stock releasing device, the combination of an operating weight, mechanical means for normally holding it in elevated inoperative position comprising a latch for releasing the rest of said means, a flexible 10 non-combustible connection connected with the weight, means operable by the movement of said non-combustible connection when the weight descends for operating stock releasing devices, the first named means comprising 15 a pivoted bar on which the weight is adapted to rest and the latch being pivoted in position with respect to the bottom of the weight so as to depend below the weight and having a horizontal surface for receiving the 20 free end of said bar, whereby when the latch is swung backwardly the bar will be released, said latch having a horizontal and a vertical arm, a flexible connection extending horizontally from the end of the vertical arm, 25 and a flexible connection extending vertically upward from the end of the horizontal arm, flexible connections being partly of a material destructible by heat running from the latch around the building adapted to release the latch when either of said connections parts, thus permitting said holding 30 means to be released and the weight to drop.
3. In a stock releasing device, the combination of an operating weight, mechanical 35 means for supporting said weight in elevated position comprising a latch, means arranged to be released in case of fire for moving the latch to release said mechanical means and allow the weight to drop, a flexible 40 non-combustible connection passing near the weight and extending in two directions from it, means connected with the upper part of the weight and projecting over said flexible connection for pulling the connection 45 down when the weight drops, and supports on each side of the weight for the flexible connection, whereby the dropping of the weight will draw both sides of said flexible connection toward each other over said supports, and means operated by said connection 50 for releasing stock.

4. In a stock releasing device the combination with an operating weight, of mechanical means for normally supporting the weight in elevated inoperative position, a flexible connection connected with said means and adapted to operate it, said flexible connection being partly of a material destructible by heat and running from said 55 means around the building, whereby upon the parting of said flexible connection at any point the weight will be released and allowed to drop, a flexible non-combustible connection with which the weight is connected 60 extending across the weight so as to pro-

vide two strands projecting in opposite directions therefrom and connected with the weight whereby when the weight drops both strands of said non-combustible connection will be pulled toward the weight, means 70 connected with one strand for releasing stock, and means connected with the other strand for giving an alarm.

5. In a device of the character described, the combination of an operating weight, 75 means constructed and adapted to be released in case of fire to let the weight drop, two guides over the weight located near each other, a flexible connection for operating stock releasing devices passing over the two 80 guides, and means connected with the weight extending between said guides for engaging the connection on the opposite side and normally leaving the connection straight between the guides whereby the descent of the 85 weight will pull both ends of said connection lengthwise toward the weight by pulling said means and the connection down between said guides.

6. In a stock releasing device, the combination with an operating weight, of means for normally supporting the weight in elevated inoperative position, a flexible connection connected with said means and adapted to operate it, part of said flexible connection 90 being destructible by heat, two guides arranged near together, said connection passing between said guides and having two strands extending in opposite directions, one over each of said guides, a weight on the end 100 of each strand, counterbalancing each other in inoperative position, and means for releasing the weight connected with said connection, whereby upon the parting of either strand its weight will be disconnected from 105 the system and the other weight will be free to operate the weight releasing means.

7. In a stock releasing device, the combination with an operating weight, of means for normally supporting the weight in elevated inoperative position, a flexible connection comprising a plurality of strands connected with said means and adapted to operate it, part of said flexible connection being 110 destructible by heat, a weight on the end of each strand counterbalancing each other in inoperative position, and means for releasing the first named means and consequently the weight connected with said connection whereby upon the parting of either strand 115 the other weight will be free to operate the weight releasing means.

8. In a stock releasing device, the combination with an operating weight, of means for normally supporting the weight in elevated inoperative position, a separate destructible flexible connection connected with said means and adapted to operate it, whereby upon the parting of said flexible connection the weight will be allowed to drop, a 120 125 130

flexible non-combustible connection with which the weight is connected but not supporting it, said non-combustible connection projecting in opposite directions from the weight, whereby when the weight drops both ends of said non-combustible connection will be pulled toward the weight, means on the last named connection for releasing stock,

means on the connection for giving an alarm, and counterweights depending from the ends of said connection and holding it taut.

In testimony whereof I have hereunto affixed my signature.

JOHN HILL.
